(57) **ABSTRACT**

A centrifugal compressor includes an impeller, a plurality of diffuser vanes arranged in a circumferential direction on a radially outer side of the impeller, and a housing which includes a scroll portion forming a scroll flow passage positioned on a radially outer side of the plurality of diffuser vanes. The plurality of diffuser vanes include at least one first diffuser vane positioned in an angular range between a tongue section of the scroll portion and a scroll end of the scroll portion in the circumferential direction, and a second diffuser vane positioned outside the angular range. A vane outlet angle formed by a tangent line at a trailing edge to a pressure surface of each of the plurality of diffuser vanes satisfies $\beta_1 < \beta_2$, where β_1 is the vane outlet angle of the first diffuser vane, and β_2 is the vane outlet angle of the second diffuser vane.

DIFFUSER VANE GEOMETRY FOR A
CENTRIFUGAL COMPRESSOR AND
TURBOCHARGER

TECHNICAL FIELD

The present disclosure relates to a centrifugal compressor and a turbocharger.

BACKGROUND

As a centrifugal compressor applied to a turbocharger or the like, a centrifugal compressor may be used, which is provided with a diffuser vane for decreasing the velocity and increasing the pressure of a fluid downstream of an impeller for applying a centrifugal force to the fluid.

For example, Patent Document 1 discloses a centrifugal gas compressor which includes a plurality of diffuser vanes each configured to convert the flow velocity of a fluid from an impeller into a pressure and a scroll for guiding the flow of the fluid from the diffuser vanes to the outside. In the centrifugal gas compressor, in order to improve efficiency of a diffuser, the plurality of diffuser vanes are arranged as an asymmetrical pattern in the circumferential direction of the fluid in the scroll in consideration of a pressure distribution in the circumferential direction. That is, the shapes, the orientations, or the positions of the plurality of diffuser vanes arranged in the circumferential direction are not uniform.

CITATION LIST

Patent Literature

Patent Document 1: JP2013-519036A (translation of a PCT application)

SUMMARY

Technical Problem

Meanwhile, in a centrifugal compressor with a diffuser vane, the shape of a flow passage changes from a spiral shape to a linear shape in the vicinity of the outlet of a scroll flow passage, and thus a circumferential component of a flow velocity decreases in an angular range in the vicinity of the outlet of the scroll flow passage in the circumferential direction as compared with another angular range. Accordingly, the flow stalls on a pressure surface of the diffuser vane (negative stall), which may cause separation.

In this regard, in the centrifugal gas compressor described in Patent Document 1, although the plurality of diffuser vanes are arranged as the asymmetrical pattern in consideration of the pressure distribution in the circumferential direction, Patent Document 1 does not disclose a specific configuration for suppressing separation of the flow in the diffuser vanes in the vicinity of the outlet of the scroll flow passage.

In view of the above, an object of at least one embodiment of the present disclosure is to provide a centrifugal compressor and a turbocharger including the same. The centrifugal compressor can suppress separation of a flow in diffuser vanes in an angular range in the vicinity of the outlet of a scroll flow passage.

Solution to Problem

(1) A centrifugal compressor according to at least one embodiment of the present invention includes an impeller, a

2

plurality of diffuser vanes arranged in a circumferential direction on a radially outer side of the impeller, and a housing which includes a scroll portion forming a scroll flow passage positioned on a radially outer side of the plurality of diffuser vanes. The plurality of diffuser vanes include at least one first diffuser vane positioned at least partially in an angular range between a tongue section of the scroll portion and a scroll end of the scroll portion in the circumferential direction, and a second diffuser vane positioned outside the angular range. A vane outlet angle formed by a tangent line at a trailing edge to a pressure surface of each of the plurality of diffuser vanes satisfies $\beta_1 < \beta_2$, where β_1 is the vane outlet angle of the first diffuser vane, and β_2 is the vane outlet angle of the second diffuser vane.

As described above, in the angular range between the tongue section of the scroll portion and the scroll end of the scroll portion in the circumferential direction (that is, an angular range in the vicinity of the outlet of the scroll flow passage), a flow stalls on the pressure surface of each of the diffuser vanes (negative stall), which may cause separation. This is considered because in the angular range in the vicinity of the outlet of the scroll flow passage, the flow direction of a fluid is turned, and a circumferential component of a flow velocity is decreased as compared with another angular range, and thus an effect of pressing a flow in the vicinity of each of the diffuser vanes against the pressure surface thereof is small.

In this regard, with the above configuration (1), since the vane outlet angle β_1 of the first diffuser vane positioned in the angular range in the vicinity of the outlet of the scroll flow passage where the circumferential component of the flow velocity decreases is smaller than the vane outlet angle β_2 of the second diffuser vane positioned outside the angular range, the pressure surface in the vicinity of the trailing edge of the first diffuser vane is positioned upstream in the rotational direction of the impeller as compared with the second diffuser vane, making it possible to suppress separation on the side of the pressure surface of the first diffuser vane.

(2) In some embodiments, in the above configuration (1), on a linear vane-arrangement mapping of the plurality of diffuser vanes, a camber angle α_1 of the first diffuser vane and a camber angle α_2 of the second diffuser vane satisfy $\alpha_1 > \alpha_2$.

A camber angle of each of the diffuser vanes is an angle between a tangent line at the leading edge and a tangent line at the trailing edge of a camber line of each of the diffuser vanes.

With the above configuration (2), since the camber angle α_1 of the first diffuser vane is larger than the camber angle α_2 of the second diffuser vane, the pressure surface of the first diffuser vane deviates upstream in an impeller rotational direction with reference to the leading edge, as compared with the second diffuser vane. Thus, it is possible to achieve the above configuration (1).

(3) In some embodiments, in the above configuration (1) or (2), a vane thickness t_1 at the trailing edge of the first diffuser vane and a vane thickness t_2 at the trailing edge of the second diffuser vane satisfy $t_1 > t_2$.

With the above configuration (3), since the vane thickness t_1 at the trailing edge of the first diffuser vane is larger than the vane thickness t_2 at the trailing edge of the second diffuser vane, it is possible to deviate the pressure surface of the first diffuser vane upstream in the impeller rotational direction without greatly changing the position of the suc-

tion surface of the first diffuser vane, as compared with the second diffuser vane. Thus, it is possible to achieve the above configuration (1).

(4) In some embodiments, in any one of the above configurations (1) to (3), a stagger angle formed by a chordwise direction of each of the plurality of diffuser vanes with respect to the radial direction satisfies $\gamma_1 < \gamma_2$, where γ_1 is the stagger angle of the first diffuser vane, and γ_2 is the stagger angle of the second diffuser vane.

The above-described stagger angle may be a stagger angle at the leading edge or the trailing edge of each of the diffuser vanes.

With the above configuration (4), since the stagger angle γ_1 of the first diffuser vane is smaller than the stagger angle γ_2 of the second diffuser vane, the pressure surface of the first diffuser vane deviates upstream in an impeller rotational direction with reference to the leading edge, as compared with the second diffuser vane. Thus, it is possible to achieve the above configuration (1).

(5) In some embodiments, in the above configuration (4), in a cross section orthogonal to an axial direction, the first diffuser vane has the same cross-sectional shape as the second diffuser vane.

Satisfying the magnitude relationship between the stagger angles γ_1 and γ_2 described in the above configuration (4), it is possible to achieve the above configuration (1) even if the first diffuser vane having a common cross-sectional shape with the second diffuser vane is adopted.

(6) A turbocharger according to at least one embodiment of the present invention includes the centrifugal compressor according to any one of the above configurations (1) to (5).

With the above configuration (6), since the vane outlet angle β_1 of the first diffuser vane positioned in the angular range in the vicinity of the outlet of the scroll flow passage where the circumferential component of the flow velocity decreases is smaller than the vane outlet angle β_2 of the second diffuser vane positioned outside the angular range, the pressure surface in the vicinity of the trailing edge of the first diffuser vane is positioned upstream in the rotational direction of the impeller as compared with the second diffuser vane, making it possible to suppress separation on the side of the pressure surface of the first diffuser vane.

Advantageous Effects

According to at least one embodiment of the present invention, a centrifugal compressor and a turbocharger including the same are provided. The centrifugal compressor can suppress separation of a flow in diffuser vanes in an angular range in the vicinity of the outlet of a scroll flow passage.

BRIEF DESCRIPTION OF DRAWINGS

FIG. 1 is a schematic cross-sectional view of a centrifugal compressor along the axial direction according to an embodiment.

FIG. 2A is a view showing the interior of the centrifugal compressor shown in FIG. 1.

FIG. 2B is a partial enlarged view of FIG. 2A.

FIG. 3 is a view showing the configuration of diffuser vanes in the centrifugal compressor according to an embodiment.

FIG. 4 is a view showing the configuration of the diffuser vanes in the centrifugal compressor according to an embodiment.

FIG. 5 is a view showing the configuration of the diffuser vanes in the centrifugal compressor according to an embodiment.

FIG. 6 is a schematic view showing the configuration of a typical centrifugal compressor 100.

DETAILED DESCRIPTION

Embodiments of the present invention will now be described in detail with reference to the accompanying drawings. It is intended, however, that unless particularly identified, dimensions, materials, shapes, relative positions and the like of components described in the embodiments shall be interpreted as illustrative only and not intended to limit the scope of the present invention.

A centrifugal compressor according to embodiments to be described below is applicable to, for example, a turbocharger. However, the application of the centrifugal compressor is not limited to the turbocharger.

FIG. 1 is a schematic cross-sectional view of the centrifugal compressor along the axial direction according to an embodiment. FIGS. 2A and 2B are views for explaining the arrangement of components of the centrifugal compressor shown in FIG. 1. FIG. 2A is a view showing the interior of the centrifugal compressor shown in FIG. 1 as viewed from the axial direction. FIG. 2B is a partial enlarged view of FIG. 2A. In order to clarify the positional relationship among the respective components, each of the components is indicated by a solid line in FIG. 2A.

As shown in FIGS. 1 and 2A, a centrifugal compressor 1 according to an embodiment includes an impeller 4 and a housing 6. The impeller 4 includes a plurality of rotor blades 5 and can rotate about a rotational axis O with a rotational shaft 2. The housing 6 houses the impeller 4 and a plurality of diffuser vanes 10 to be described later.

On the outer side of the impeller 4 in the radial direction of the centrifugal compressor 1 (to be simply referred to as the "radial direction" hereinafter), a scroll flow passage 7 formed by a scroll portion 8 of the housing 6 is provided. As shown in FIG. 2A, the scroll flow passage 7 has a flow-passage cross-sectional area from a scroll start 8a to a scroll end 8b of the scroll portion 8, which gradually increases from upstream toward downstream in a rotational direction of the impeller 4 (that is, from upstream toward downstream in a flow direction of a fluid).

The scroll flow passage 7 communicates with an outlet flow passage 17 formed by an outlet portion 16 of the housing 6. In the housing 6, the scroll portion 8 and the outlet portion 16 are connected to each other, and a tongue section 22 is formed by a part of the scroll start 8a of the scroll portion 8 and the outlet portion 16 connected to the part of the scroll start 8a.

On the radially outer side of the impeller 4 and the radially inner side of the scroll flow passage 7, a diffuser passage 9 is formed by a hub-side wall surface 18 and a shroud-side wall surface 20 of the housing 6. In the diffuser passage 9, the plurality of diffuser vanes 10 are arranged in the circumferential direction of the centrifugal compressor 1 (to be simply referred to as the "circumferential direction" hereinafter). That is, the scroll flow passage 7 is positioned on the radially outer side of the diffuser passage 9 and the plurality of diffuser vanes 10.

Each of the plurality of diffuser vanes 10 has a leading edge 24, a trailing edge 26 positioned on the radially outer side of the leading edge 24, and a pressure surface 28 and a suction surface 30 extending between the leading edge 24 and the trailing edge 26.

The diffuser vanes **10** are installed in the above-described diffuser passage **9** while being fixed to the surface of a disc-shaped mounting plate **14**. The diffuser vanes **10** may be joined to the mounting plate **14** by welding. Alternatively, the diffuser vanes **10** and the mounting plate **14** may integrally be formed by, for example, cutting work or the like.

In an illustrated example, the mounting plate **14** is installed on the shroud-side wall surface **20** forming the diffuser passage **9**. However, in other embodiments, the mounting plate **14** may be installed on the hub-side wall surface **18**.

In the centrifugal compressor **1**, a fluid (such as a gas) flowing into the impeller **4** in the axial direction of the centrifugal compressor **1** (to be simply referred to as the “axial direction” hereinafter) is accelerated and pushed out in the circumferential direction and the radial direction due to the rotation of the impeller **4**. The fluid accelerated by the impeller **4** passes through the diffuser vanes **10** disposed in the diffuser passage **9**. At this time, kinetic energy of a fluid flow is converted into pressure energy (that is, the fluid is decreased in velocity and increased in pressure). Then, the flow passing through the diffuser vanes **10** and including a velocity component in the radial direction flows into the scroll flow passage **7** and is guided to the outlet flow passage **17** downstream thereof. The centrifugal compressor **1** thus generates a high-pressure fluid.

In the centrifugal compressor **1** according to some embodiments, the plurality of diffuser vanes **10** include first diffuser vanes **11** and second diffuser vanes **12** having different vane outlet angles β .

FIG. 2B is a view showing the diffuser vanes **10** in the vicinity of the outlet of the scroll flow passage **7** of the centrifugal compressor **1** shown in FIG. 2A. Each of the vane outlet angles β of a corresponding one of the diffuser vanes **10** is an angle formed by a tangent line **LT** at the trailing edge **26** to the pressure surface **28** of the diffuser vane **10** with respect to the radial direction ($0^\circ \leq \beta \leq 90^\circ$) (that is, an angle formed by the aforementioned tangent line **LT** with respect to a radial straight line **LR_{TE}** passing through the trailing edge **26**).

More specifically, as shown in FIGS. 2A and 2B, the plurality of diffuser vanes **10** include at least one first diffuser vane **11** positioned at least partially in an angular range **A₁** (see FIG. 2A) between the tongue section **22** of the scroll portion **8** and the scroll end **8b** of the scroll portion **8**, and the second diffuser vanes **12** positioned in an angular range other than the angular range **A₁**.

Then, a vane outlet angle β_1 of the first diffuser vane **11** (see FIG. 2B) and a vane outlet angle β_2 of the second diffuser vane **12** (see FIG. 2B) satisfy the relation of $\beta_1 < \beta_2$.

FIG. 6 is a schematic view showing the configuration of a typical centrifugal compressor **100**, and is a view showing a linear vane-arrangement mapping of the diffuser vanes **10**, of the plurality of diffuser vanes **10**, positioned in the above-described angular range **A₁** (that is, the angular range between the tongue section **22** and the scroll end **8b** of the scroll portion **8**) and in the vicinity thereof, and the scroll flow passage **7** and the outlet flow passage **17** corresponding to the linear vane-arrangement mapping.

In the typical centrifugal compressor **100** shown in FIG. 6, the plurality of diffuser vanes **10** each have the same shape and are uniformly arranged at intervals in the circumferential direction. That is, the plurality of diffuser vanes **10** respectively have the above-described vane outlet angles β and angles (stagger angles) γ , which are identical to each

other. Each of the angles (stagger angles) γ is formed by a chordwise direction with respect to the radial direction.

In the angular range **A₁** in the vicinity of the outlet of the scroll flow passage **7** in the circumferential direction, the flow stalls on the pressure surface **28** of the diffuser vane **10** (in a region **32** of FIG. 6) (negative stall), which is likely to cause separation as compared with another angular range.

This is considered for the following reason. That is, as shown in FIG. 6, the fluid accelerated by the impeller (not shown in FIG. 6) flows into the diffuser passage **9** at an incident angle I , passes through the diffuser vanes **10**, and flows into the scroll flow passage **7**. A flow velocity vector **V₁** in the scroll flow passage **7** is basically a circumferential vector. In the angular range **A₁** in the vicinity of the outlet of the scroll flow passage **7**, a fluid flow is guided from the scroll flow passage **7** to the outlet flow passage **17**, turning the direction of the fluid flow and decreasing a circumferential component **V_c** of the flow velocity as compared with the other angular range. Therefore, in the angular range **A₁** in the vicinity of the outlet of the scroll flow passage, an effect of pressing the flow in the vicinity of the diffuser vanes **10** against the pressure surface **28** by the circumferential flow in the scroll flow passage **7** is small as compared with the other angular range, which is likely to cause separation of the flow on the pressure surface **28**.

In this regard, in the above-described embodiment, since the vane outlet angle β_1 of the first diffuser vane **11** positioned in the angular range **A₁** in the vicinity of the outlet of the scroll flow passage **7** is smaller than the vane outlet angle β_2 of the second diffuser vane **12** positioned outside the angular range **A₁**, the pressure surface **28** in the vicinity of the trailing edge **26** of the first diffuser vane **11** is positioned upstream in the rotational direction of the impeller **4** as compared with the second diffuser vane **12** (see a second diffuser vane **12'** indicated by a dashed line in FIG. 2B). Therefore, it is possible to suppress separation on the side of the pressure surface **28** of the first diffuser vane **11**.

The second diffuser vane **12'** shown in FIG. 2B is a virtual diffuser vane illustrated for comparison of the shape and the like with the first diffuser vane **11**, and is shown by rotary-moving about the rotational axis **O** of the centrifugal compressor **1** so that the position of the leading edge **24** of the second diffuser vane **12** positioned outside the angular range **A₁** overlaps the first diffuser vane **11**.

If the plurality of diffuser vanes **10** positioned at least partially in the above-described angular range **A₁** exist, only some of the diffuser vanes **10** may be the first diffuser vanes **11** (that is, the diffuser vanes each having the vane outlet angle β_1 satisfying the above-described relation of $\beta_1 < \beta_2$).

Some embodiments of the centrifugal compressor in which the vane outlet angle β_1 of the first diffuser vane **11** and the vane outlet angle β_2 of the second diffuser vane **12** satisfy the relation of $\beta_1 < \beta_2$ will be described below in more detail.

Each of FIGS. 3 to 5 is a view showing the configuration of the diffuser vanes **10** in the centrifugal compressor according to an embodiment. FIG. 3 is a view showing the linear vane-arrangement mapping of the diffuser vanes **10**, of the plurality of diffuser vanes **10** (including the first diffuser vanes **11** and the second diffuser vanes **12**) of the centrifugal compressor **100**, positioned in the above-described angular range **A₁** (that is, the angular range between the tongue section **22** and the scroll end **8b** of the scroll portion **8**) and in the vicinity thereof according to an embodiment. Each of FIGS. 4 and 5 is a view of the diffuser vanes **10** positioned in the above-described angular range **A₁**

and in the vicinity thereof in the centrifugal compressor as viewed from the axial direction according to an embodiment.

In FIGS. 3 and 5, the components other than the diffuser vanes 10 and the mounting plate 14 are not shown. Moreover, each second diffuser vane 12' shown in FIGS. 3 to 5 is the virtual diffuser vane illustrated for comparison of the shape and the like with the first diffuser vane 11, and is shown by rotary-moving about the rotational axis O so that the position of the leading edge 24 of the second diffuser vane 12 positioned outside the angular range A1 overlaps the first diffuser vane 11.

In an embodiment, for example, as shown in FIG. 3, on the linear vane-arrangement mapping of the plurality of diffuser vanes 10, a camber angle α_1 of the first diffuser vane 11 positioned at least partially in the angular range A1 and a camber angle α_2 of the second diffuser vane 12 positioned outside the angular range A1 satisfy $\alpha_1 > \alpha_2$.

A camber angle α of each of the diffuser vanes 10 is an angle formed between a tangent line LG at the leading edge 24 and a tangent line LH at the trailing edge 26 of a camber line LF of each of the diffuser vanes 10. Provided that P1 is an intersection point between the tangent line LG at the leading edge 24 and the tangent line LH at the trailing edge 26 described above, the camber angle α is an angle between a vector in a direction from the leading edge 24 toward the intersection point P1 and a vector in a direction from the intersection point P1 toward the trailing edge 26 ($0^\circ \leq \alpha \leq 180^\circ$) (see FIG. 3).

Thus, since the camber angle α_1 of the first diffuser vane 11 is larger than the camber angle α_2 of the second diffuser vane 12, the pressure surface 28 of the first diffuser vane 11 deviates upstream in the impeller rotational direction with reference to the leading edge 24, as compared with the second diffuser vane 12 (see the second diffuser vanes 12' each indicated by the dashed line in FIG. 3). Thus, it is possible to achieve the configuration in which the vane outlet angle β_1 of the first diffuser vane 11 and the vane outlet angle β_2 of the second diffuser vane 12 satisfy the relation of $\beta_1 < \beta_2$.

FIG. 3 shows a vane outlet angle β_1' of the first diffuser vane 11 and a vane outlet angle β_2' of the second diffuser vane 12 in the linear vane-arrangement mapping. The magnitude relationship between the vane outlet angle β_1' and the vane outlet angle β_2' in the linear vane-arrangement mapping is the same as the magnitude relationship between the vane outlet angle β_1 and the vane outlet angle β_2 . That is, in the linear vane-arrangement mapping of the diffuser vanes, the relation of $\beta_1 < \beta_2$ is also satisfied as long as $\beta_1' < \beta_2'$ holds.

In an embodiment, for example, as shown in FIG. 4, a vane thickness t_1 at the trailing edge 26 of the first diffuser vane 11 and a vane thickness t_2 at the trailing edge 26 of the second diffuser vane 12 satisfy $t_1 > t_2$.

In the exemplary embodiment shown in FIG. 4, while the suction surface 30 of the first diffuser vane 11 has the same shape as the suction surface 30 of the second diffuser vane 12, the pressure surface 28 of the first diffuser vane 11 deviates upstream in the impeller rotational direction as compared with the second diffuser vane 12. That is, a distance (vane thickness t) between the pressure surface 28 and the suction surface 30 of the first diffuser vane 11 has a special vane thickness distribution increasing from the side of the leading edge 24 toward the side of the trailing edge 26.

Since the vane thickness t_1 at the trailing edge 26 of the first diffuser vane 11 is thus larger than the vane thickness t_2 at the trailing edge 26 of the second diffuser vane 12, it is

possible to deviate the pressure surface 28 of the first diffuser vane 11 upstream in the impeller rotational direction without greatly changing the position of the suction surface 30 of the first diffuser vane 11, as compared with the second diffuser vane 12 (see the second diffuser vane 12' indicated by the dashed line in FIG. 4). Thus, it is possible to achieve the configuration in which the vane outlet angle β_1 of the first diffuser vane 11 and the vane outlet angle β_2 of the second diffuser vane 12 satisfy the relation of $\beta_1 < \beta_2$.

In an embodiment, for example, as shown in FIG. 5, the stagger angle γ formed by the chordwise direction of each of the plurality of diffuser vanes 10 with respect to the radial direction satisfies $\gamma_1 > \gamma_2$, where γ_1 is a stagger angle of the first diffuser vane 11, and γ_2 is a stagger angle of the second diffuser vane 12.

The stagger angle γ is an angle formed by the chordwise direction (a direction of a straight line passing through the leading edge 24 and the trailing edge 26) of each of the diffuser vanes 10 with respect to the radial direction ($0^\circ \leq \gamma \leq 90^\circ$).

The above-described stagger angle γ may be a stagger angle γ_A with reference to the leading edge 24 or a stagger angle γ_B with reference to the trailing edge 26 of each of the diffuser vanes 10. The stagger angle γ_A with reference to the leading edge 24 of each of the diffuser vanes 10 is an angle between a straight line Lc in the chordwise direction of each of the diffuser vanes 10 and a radial straight line passing through the leading edge 24 of each of the diffuser vanes 10 (see FIG. 5). Moreover, the stagger angle γ_B with reference to the trailing edge 26 of each of the diffuser vanes 10 is an angle between a straight line Lc in the chordwise direction of each of the diffuser vanes 10 and a radial straight line passing through the trailing edge 26 of each of the diffuser vanes 10 (see FIG. 5).

In the exemplary embodiment shown in FIG. 5, a stagger angle $\gamma_A 1$ with reference to the leading edge 24 of the first diffuser vane 11 is smaller than a stagger angle $\gamma_A 2$ with reference to the leading edge 24 of the second diffuser vane 12 (that is, $\gamma_A 1 < \gamma_A 2$ is satisfied).

Moreover, in the exemplary embodiment shown in FIG. 5, a stagger angle $\gamma_B 1$ with reference to the trailing edge 26 of the first diffuser vane 11 is smaller than a stagger angle $\gamma_B 2$ with reference to the trailing edge 26 of the second diffuser vane 12 (that is, $\gamma_B 1 < \gamma_B 2$ is satisfied).

Thus, since the stagger angle γ_1 ($\gamma_A 1$ or $\gamma_B 1$) of the first diffuser vane 11 is smaller than the stagger angle γ_2 ($\gamma_A 2$ or $\gamma_B 2$) of the second diffuser vane 12, the pressure surface 28 of the first diffuser vane 11 deviates upstream in the impeller rotational direction with reference to the leading edge 24, as compared with the second diffuser vane 12 (see the second diffuser vanes 12' indicated by the dashed line in FIG. 5). Thus, it is possible to achieve the configuration in which the vane outlet angle β_1 of the first diffuser vane 11 and the vane outlet angle β_2 of the second diffuser vane 12 satisfy the relation of $\beta_1 < \beta_2$.

Furthermore, in the exemplary embodiment shown in FIG. 5, in a cross section orthogonal to the axial direction, the cross-sectional shape of the first diffuser vane 11 is the same as the cross-sectional shape of the second diffuser vane 12.

Since the stagger angle γ_1 of the first diffuser vane 11 and the stagger angle γ_2 of the second diffuser vane satisfy the relation of $\gamma_1 < \gamma_2$, it is possible to achieve the configuration in which the vane outlet angle β_1 of the first diffuser vane 11 and the vane outlet angle β_2 of the second diffuser vane 12 satisfy $\beta_1 < \beta_2$, even if the first diffuser vane having the

common cross-sectional shape with the second diffuser vane 12 is adopted as in the exemplary embodiment shown in FIG. 5.

Embodiments of the present invention were described in detail above, but the present invention is not limited thereto, and various amendments and modifications may be implemented.

Further, in the present specification, an expression of relative or absolute arrangement such as "in a direction", "along a direction", "parallel", "orthogonal", "centered", "concentric" and "coaxial" shall not be construed as indicating only the arrangement in a strict literal sense, but also includes a state where the arrangement is relatively displaced by a tolerance, or by an angle or a distance whereby it is possible to achieve the same function.

For instance, an expression of an equal state such as "same" "equal" and "uniform" shall not be construed as indicating only the state in which the feature is strictly equal, but also includes a state in which there is a tolerance or a difference that can still achieve the same function.

Further, for instance, an expression of a shape such as a rectangular shape or a cylindrical shape shall not be construed as only the geometrically strict shape, but also includes a shape with unevenness or chamfered corners within the range in which the same effect can be achieved.

As used herein, the expressions "comprising", "containing" or "having" one constitutional element is not an exclusive expression that excludes the presence of other constitutional elements.

The invention claimed is:

1. A centrifugal compressor, comprising: an impeller; a plurality of diffuser vanes arranged in a circumferential direction on a radially outer side of the impeller; and

a housing which includes a scroll portion forming a scroll flow passage positioned on a radially outer side of the plurality of diffuser vanes,

wherein the plurality of diffuser vanes include:

at least one first diffuser vane positioned at least partially in an angular range between a tongue section of the scroll portion and a scroll end of the scroll portion in the circumferential direction; and
a second diffuser vane positioned outside the angular range,

wherein a vane outlet angle formed by a tangent line at a trailing edge to a pressure surface of each of the plurality of diffuser vanes satisfies $β_1 < β_2$, where $β_1$ is the vane outlet angle of the first diffuser vane, and $β_2$ is the vane outlet angle of the second diffuser vane, and wherein, on a linear vane-arrangement mapping of the plurality of diffuser vanes, a camber angle $α_1$ of the first diffuser vane and a camber angle $α_2$ of the second diffuser vane satisfy $α_1 > α_2$.

2. The centrifugal compressor according to claim 1, wherein a stagger angle formed by a chordwise direction of each of the plurality of diffuser vanes with respect to the radial direction satisfies $γ_1 < γ_2$, where $γ_1$ is the stagger angle of the first diffuser vane, and $γ_2$ is the stagger angle of the second diffuser vane.

3. The centrifugal compressor according to claim 2, wherein, in a cross section orthogonal to an axial direction, the first diffuser vane has the same cross-sectional shape as the second diffuser vane.

4. The centrifugal compressor according to claim 1, wherein the vane outlet angle $β_1$ of each of the first diffuser vanes is smaller than the vane outlet angle $β_2$ of each of all the second diffuser vanes positioned outside the angular range.

5. The centrifugal compressor according to claim 1, wherein the plurality of diffuser vanes have an arrangement center which is coincident with a rotational center of the impeller.

6. The centrifugal compressor according to claim 1, wherein an angle formed by the tangent line at the trailing edge to the pressure surface of each of the plurality of diffuser vanes with respect to a straight line extending from an arrangement center of the plurality of diffuser vanes to the trailing edge of each of the diffuser vanes is larger in the first diffuser vane than in the second diffuser vane.

7. A turbocharger, comprising:
the centrifugal compressor according to claim 1.

8. A centrifugal compressor, comprising:

an impeller;
a plurality of diffuser vanes arranged in a circumferential direction on a radially outer side of the impeller; and
a housing which includes a scroll portion forming a scroll flow passage positioned on a radially outer side of the plurality of diffuser vanes,

wherein the plurality of diffuser vanes include:

at least one first diffuser vane positioned at least partially in an angular range between a tongue section of the scroll portion and a scroll end of the scroll portion in the circumferential direction; and
a second diffuser vane positioned outside the angular range,

wherein a vane outlet angle formed by a tangent line at a trailing edge to a pressure surface of each of the plurality of diffuser vanes satisfies $β_1 < β_2$, where $β_1$ is the vane outlet angle of the first diffuser vane, and $β_2$ is the vane outlet angle of the second diffuser vane, and

wherein a vane thickness t_1 at the trailing edge of the first diffuser vane and a vane thickness t_2 at the trailing edge of the second diffuser vane satisfy $t_1 > t_2$.

9. A turbocharger, comprising:
the centrifugal compressor according to claim 8. 5
